MOTOR WITH EXTRA COOLING OF THE AIR OR FUEL MIXTURE
BEFORE ADMISSION INTO THE WORKING CYLINDER

Filed July 25, 1924

UNITED STATES PATENT OFFICE.

OSCAR WALFRID HULT, OF STOCKHOLM, SWEDEN.

MOTOR WITH EXTRA COOLING OF THE AIR OR FUEL MIXTURE BEFORE ADMISSION
INTO THE WORKING CYLINDER.

Application filed July 25, 1924, Serial No. 728,232, and in Sweden November 28, 1923.

This invention refers to a method of bringing about efficient cooling of the air or the fuel mixture for internal combustion motors, that the air or mixture, as the case 5 may be, after having been compressed and cooled is allowed to re-expand and to exert its pressure upon the compressor piston, during which process it is cooled in order to be introduced into the working cylinder at the 10 next stroke of the compressor piston.

On the accompanying drawing there is shown by way of example a four-stroke motor constructed according to this invention. Fig. 1 is a vertical section of the motor 15 and shows the compressor piston in its upper extreme position. Fig. 2 shows the location of cooling pipes in relation to the compressor head, and Fig. 3 shows a cam for the positive driving of the motor valves, this cam 20 acting in both directions.

The air or fuel mixture is compressed by a piston *a* propelled by the engine crank, moving in a cylinder, in which the air or fuel mixture enters through a suction valve *i*. The upper part of the compression chamber for the air or the motive mixture is formed by pipes *b*, which are fixed in the compressor cylinder head and the lower ends of which communicate with the chamber in the compressor cylinder, while the upper ends are closed. These pipes are surrounded by the cooling water in a cooling jacket *c*, which in the example shown surrounds not only the compression cylinder 25 but also the working cylinder *h* of the motor, in which cylinder the motor or working piston *g* moves. It should, however, be observed that it is more suitable that the two cylinders have each a separate water jacket. From the chamber in the compressor cylinder there extends a pipe *d* to a chamber *e* arranged in the head of the working cylinder *h*, from which chamber the air or mixture flows into the working cylinder *h* past a spring actuated valve *f*. By 30 means of another spring actuated valve the exhaust of the combustion products from the working cylinder *h* is regulated. These two valves are driven from the motor shaft 45 by means of a cam *k* (Fig. 3).

The motor described works in the following manner.

The air or mixture is in the shown position of the compressor piston *a* compressed

and fills the cooling pipes *b*, which are surrounded by the water circulating in the cooling jacket *c*. At the same time the pipe *d* and the valve casing *e* are filled with compressed air or mixture, and the spring pressure upon the valve *f* is so great that the 55 valve tightens against the pressure of the air or the mixture, which pressure may reach 3 to 4 atmospheres or even more.

The air or mixture, which in the shown position of the compressor piston *a* has been deprived of the greater part of its compression heat by the greater part of its volume being enclosed in the water cooled pipes *b*, drives by its pressure the piston *a* downward, until it has expanded down to atmospheric pressure, thereat being cooled according to the usual formula for the cooling of air while expanding during work, with the exception of the slight heating which occurs on account of the contact with the 60 walls of the chamber.

When the compressor piston *a* after the expansion stroke has reached its lower extreme position, the motor piston *g*, which works on the four stroke principle, has just completed its ordinary exhaust stroke. The valve *f* opens, and the piston *g* begins to move downward, while the compressor piston *a* simultaneously moves upward, the cooled air then rushing into the working cylinder *h*. 75

At the next downward movement of the compressor piston *a* the next charge of air or mixture is being sucked in through the suction valve *i*, after which a new compression occurs during the cooling of the air by 80 means of the cooling device described, and the course described will be repeated.

As will be seen from the description, also the compressor piston works on the four-stroke principle: suction, compression, expansion and exhaust, only with the difference that the piston of the working cylinder during the said exhaust serves as a suction member, which is an advantage and prevents the rise of pressure of the cooled air, whereby all unnecessary increase of heat during the suction stroke in the working cylinder is obviated, and occurs first during the compression of the charge in the said cylinder. 85

The suction valve *i* of the air pump or compressor is able to serve as a regulator, so that fresh air or mixture flows through the same, e. g. if the air or mixture, through the 100

different sizes of the pistons, is rarefied to or below atmospheric pressure, e. g. to 0.9 atmospheric absolute pressure, in which case the working cylinder thus receives a portion 5 of the air or mixture through the said valve.

The advantages of this device over such devices as are mentioned e. g. in the U. S. Patent application No. 621,919 of the applicant are the following ones:

10 1. The air (or mixture) compressed by the compressor is cooled already during the compression stroke, so that, when the compressor piston turns, it has been deprived of the greater part of the compression heat, 15 whereby the work of compression is reduced.

2. By immediately allowing the compressed and cooled quantity of air to expand in the compressor itself, and thereby pressure upon the compressor piston return the 20 greater part of the work expended in compression, the motor obtains an effect increased to a corresponding degree.

3. The cooling becomes more efficient, as the air is allowed to exert its expansion pressure in the strongly cooled compression cylinder, where re-heating is considerably less than it can become in the working cylinder heated by explosion.

4. The pressure between the air and cylinder walls can be reduced, so that it is less than atmospheric pressure, after the expansion or cooling stroke is completed, i. e. when the cooled air is introduced into the working cylinder of the motor, by making the stroke 35 volume of the said cylinder greater than the stroke volume of the compressor cylinder which causes a corresponding rarefaction of air.

5. The device becomes remarkably simple 40 by the ordinary four stroke cycle without any extra member regulating the course of working in the compressor, disregarding the small suction valve *i*, which requires no positive driving.

45 As to the rarefaction of air mentioned in the preceding clause 4 it may be observed that in order to enable the same to take place by the stroke volume of the working cylinder being made greater than that of 50 the compression cylinder, the suction valve *i* should be positively governed in such a manner that only that quantity of air (or mixture), for which there is room in the compressor cylinder, is admitted into the 55 working cylinder, for otherwise the latter cylinder may during its suction stroke receive air (or mixture) through the suction valve *i*.

This regulation of the admission of air 60 (or mixture) may according to the preceding description also be arranged in such a manner, that the degree of charging in the working cylinder of the motor is determined by the same, independent of the greater or less volume of the compressor, e. g. in such

a manner that the motor when running normally, receives only so much air or mixture as finds room in the compressor cylinder, in which case this cylinder receives a 73% charge, which corresponds to the increased 70 condensation of the air or mixture as a consequence of being cooled to 0° C. at the beginning of the compression in the working cylinder, or in such a manner that the positively governed suction valve *i* or, if desired, 75 an extra suction valve (or both), if a greater degree of charging or a complete charge is wished, allows the entrance of air or mixture e. g. during the whole suction stroke of the working piston, if, in case of need, an 80 increase of the volumetric effect of the motor beyond the ordinary is wished.

As will be seen from the process described, the intended method of working should with absolute certainty be obtained to such a high 85 degree that the temperature of 0° C. or below can be reached before the commencement of compression in the working cylinder of the motor, without any increased loss of 90 power needing to arise through a high compression in the compressor or air pump.

The motor can also be constructed in any other manner than the one stated with regard to various requirements, e. g. when the greatest possible amount of power with 95 somewhat reduced economy is preferred, the stroke volume of the compressor may be equally great as or even greater than the stroke volume of the working cylinder, by which means a heavier or a greater quantity of air is admitted into the motor, besides what will be gained through the condensation caused by the cooling.

The compressor may be provided with two or more pistons, located in a corresponding 105 number of cylinders, or it may be double-acting, e. g. in a two stroke motor or in a two cylinder four stroke motor with a compressor common to the cylinders.

Even the cooling device may be arranged 110 in any other manner than that stated, e. g. the air or mixture may during the compression be made to circulate through tubes cooled in some suitable manner, by which means the cooling can be brought about in 115 a shorter time, if desired, e. g. in the case of very high speed motors.

Having now described my invention, what I claim as new and desire to secure by Letters Patent is:

1. The method of effecting a double cooling of a gaseous mixture to be used in an internal combustion engine, consisting in first compressing said mixture and simultaneously subjecting the same to a cooling action, then allowing the mixture to expand during further cooling and finally introducing the mixture into the engine.

2. A method as claimed in claim 1, including the step of utilizing the expansion 130

of the charge to impart an impulse to the engine.

3. An internal combustion engine including in combination a jacketed compression cylinder, a jacketed working cylinder, in communication therewith, pistons operating in said cylinders, a main shaft to which both of said pistons are connected, intake valves for both of said cylinders, a cooling device 10 in the jacketed head of the compression cylinder, and means for controlling the operation of the intake valve of the working cylinder in timed relation with the operation of the intake valve of the compression cylinder.

4. An arrangement as claimed in claim 3, wherein an exhaust valve is provided for the

working cylinder, and operated by the means which operates the intake valve for the said cylinder and in timed relation with respect to the operation of the said intake valve.

5. An arrangement as claimed in claim 3, wherein the piston of the compression cylinder is of less displacement than the piston of the working cylinder and wherein said pistons are connected in opposed relation to the shaft and operate on the four stroke cycle, substantially as and for the purposes set forth.

In witness whereof I have hereunto set my hand.

OSCAR WALFRID HULT.
